UNITED STATES PATENT OFFICE.

GEORGE A. BURNHAM, OF SAUGUS, MASSACHUSETTS, ASSIGNOR TO SEARS B. CONDIT, JR.,
OF BROOKLINE, MASSACHUSETTS.

ALTERNATING-CURRENT SOLENOID.

1,266,917.

Specification of Letters Patent. Patented May 21, 1918.

Application filed September 28, 1916. Serial No. 122,776.

To all whom it may concern:

Be it known that I, GEORGE A. BURNHAM, a citizen of the United States, residing at Saugus, in the county of Essex and State of 5 Massachusetts, have invented an Improvement in Alternating-Current Solenoids, of which the following is a specification.

This invention relates to alternating current solenoids, and has for its object the 10 construction of an improved form of solenoid adapted to be associated with a circuit-breaker or switch of any usual or suitable structure, and which is simple, may be easily and cheaply manufactured, and is 15 adapted to operate effectively when the condition of the circuit requires it, and the usual humming noise, due to the alternations of the current, is reduced to such an extent as to be inconsequential.

20 Figure 1 is a side elevation and partial vertical section of an alternating current solenoid embodying this invention.

Fig. 2 is a plan view of a supporting spring for the winding which may be employed.

25 10 represents the solenoid winding or coil which is arranged between the heads 12, 12, and is fixed to a center tube 13, of brass or other non-magnetic material. Said tube extends at each end beyond the heads. Within the tube 13, at its upper end-portion, the top core-piece 15 is arranged, which is secured to said tube by rivets or other suitable means, thus the winding and tube and top 30 core-piece are rigidly attached together.

The tube with its attached elements is disposed in an iron shell or case 20, of any suitable formation, and the upper end-portion of the tube and core-piece is loosely arranged in a center hole in the top wall of 40 said case, and hence is movable freely therein, in a vertical direction. Also, within the tube 13, a relatively movable core-piece 25 is arranged, said core-piece being made of 45 slightly lesser diameter than the internal diameter of the tube, so as to be freely movable therein. Said movable core-piece has attached to its upper end a stem 26, which is extended vertically through a center hole 50 27, extended through the top core-piece, and is movable longitudinally therein, and said stem has at its upper end a head 28, which is adapted to limit the downward movement of the core-piece 25 when the winding is de-

energized, and the core-piece is in retracted 55 position.

The winding rests upon a flat spring element 30, which, as shown in Fig. 2, comprises an intermediate circular portion with laterally extended end-portions, and said 60 circular portion engages the lowermost head 12 of the winding and encircles the tube to form a lower guide therefor, and the extremities of the end-portions freely enter recesses 31 formed in the case, and said spring 65 is adapted to be held in place by an end-piece 35, which is attached to the bottom of the case, said end-piece being extended over the recesses which receive the extremities of the end-portions of the spring. 70

When an alternating current of sufficient value is impressed on the winding, the movable core-piece is moved into and held in attracted position, as represented by full lines, Fig. 1, but, when the current value falls below a predetermined value, said core-piece falls into the dotted-line position, such downward movement being limited by the head on the stem of the core-piece. 75

The top core-piece and the relatively movable core-piece are adapted to function as 80 a single element when the current flows through the winding of sufficient voltage to attract the movable core-piece and hold the two core-pieces in engagement. 85

When the current flows through the winding and the relatively movable core-piece is attracted, the magnetic centers of the winding of the combined core-pieces may be indicated at 50, and under such conditions, the 90 combined core-pieces and the winding will all vibrate bodily in the shell or case, and all said elements will vibrate in unison or approximately so, and any relative variation in the vibrations will be so slight that they 95 will not be sufficient to produce a humming sound of any consequence.

The magnetic center of the coil in the prior art is stationary, and as there is a tendency for the magnetic center of the core-piece to 100 coincide with the magnetic center of the coil, it is evident that with a single phase alternating current there is a tendency for the core-pieces to disengage as the current passes through zero and return to attracted 105 position when the current reaches its maximum value. Such an arrangement results in an undesirable noise. It is evident that

if the magnetic center of the core-pieces and the magnetic center of the coil are in coincidence, or if the distance between these two centers is substantially constant, it is 5 evident there will be no practical separation between the relatively movable core-piece and the top core-piece when the current passes through maximum to zero. Therefore, this arrangement and operation of the 10 device will be practically noiseless.

I claim:—

1. An alternating current solenoid comprising a winding and support therefor, yielding means interposed between said 15 winding and support permitting a movement of said winding relative to said support, a top core-piece rigidly connected with said winding, a relatively-movable core-piece arranged within the winding and adapted for 20 engagement with the top core-piece, said winding and top core-piece and the relatively-movable core-piece all adapted to vibrate substantially in unison when an alternating current flows through the winding of 25 sufficient value to hold the relatively movable core-piece in engagement with the top core-piece.

2. An alternating current solenoid comprising a winding, and support therefor, means interposed between said winding and 30 support permitting a movement of said winding relative to said support, a tube, and a top core-piece all rigidly connected together, a relatively-movable core-piece arranged within the tube and adapted for 35 engagement with the top core-piece, said winding and the elements connected therewith and the movable core-piece all adapted to vibrate substantially in unison when an alternating current flows through the winding of 40 sufficient voltage to cause the movable core-piece to be held in engagement with the top core-piece.

3. An alternating current solenoid comprising a shell having a center hole in its 45 top wall, a winding arranged in the shell, a tube to which said winding is fixed, the ends of which extend beyond the ends of the winding, the upper end of said tube extending through the center hole of the shell, a top core-piece arranged within and fixed to the upper end-portion of the tube, a relatively-movable core-piece arranged in said tube below the top core-piece having a headed stem which extends through the hole in 50 the top core-piece, and a supporting-spring connected with the shell adapted to support the winding.

4. An alternating current solenoid comprising an iron shell having a guide-hole in its top-wall, a winding arranged in said shell, a tube to which said winding is secured, the upper end of which is arranged in 55 and guided by the hole in said shell, a top core-piece arranged in the upper end-portion

of said tube and secured thereto, a relatively-movable core-piece arranged within the tube, said core-piece being movable into and out of engagement with the top core-piece, a spring adapted to yieldingly support the winding having a circular portion intermediate its length which encircles the tube and serves as a guide for the lower end thereof, the winding, tube and core-pieces being adapted to vibrate substantially in 75 unison when an alternating current flows through the winding of a voltage sufficient to cause the relatively-movable core-piece to be held in engagement with the top core-piece.

5. An alternating current solenoid comprising a winding, a top core-piece rigidly connected thereto, and a relatively movable bottom core-piece, and means for maintaining the magnetic centers of the winding and 80 core-pieces in approximately a fixed relation to each other when an alternating current flows through the winding of a value sufficient to cause the relatively movable core-piece to engage the top core-piece.

6. An alternating current solenoid comprising a support, a coil relatively movable with respect to said support and a core relatively movable with respect to said coil, whereby said core and coil are adapted for 95 simultaneous vibration under the influence of an alternating current.

7. An alternating current solenoid, including a coil, a support therefor, yielding means interposed between said coil and support and a core movably arranged within said coil, said coil and core adapted for substantially simultaneous motion under the influences of an alternating current.

8. An alternating current magnet, including a support, a core piece relatively movable with respect to said support, a winding associated therewith, a core relatively movable with respect to said core piece, and means permitting the substantially simultaneous vibration of said core piece and movable core under the influence of an alternating current.

9. An alternating current magnet including a winding, a support therefor, a core piece associated with said winding, means supporting said core piece admitting of movement thereof relative to said support, a core movably disposed with respect to said core piece and adapted to be restrained from free movement in one direction by said core piece in the energized condition of said winding, said movable mounting of said core piece permitting the substantially simultaneous vibration of said core piece and core relative to said support under the influence of an alternating flux.

10. An alternating current solenoid comprising a support, a coil arranged thereon, a core movably arranged within said coil

and means permitting the simultaneous vibration of said core and coil relative to said support under the influence of an alternating current.

- 5 11. An alternating current solenoid comprising a support, a coil supported thereby, a core movably arranged within said coil and means permitting the substantial coincidence of the magnetic centers of said core

and coil during the energization of said coil 10 by an alternating current.

In testimony whereof, I have signed my name to this specification in the presence of two subscribing witnesses.
